UNITED STATES PATENT OFFICE.

CHARLES R. CRANE, 2D, OF CHICAGO, ILLINOIS, ASSIGNOR TO CRANE CO., OF CHICAGO, ILLINOIS, A CORPORATION OF ILLINOIS.

DESIGN FOR A LAVATORY.

Application filed July 22, 1927. Serial No. 22,842. Term of patent 14 years.

To all whom it may concern:

Be it known that I, CHARLES R. CRANE, II, a citizen of the United States, residing at Chicago, in the county of Cook, and State of Illinois, have invented a new, original and ornamental Design for Lavatory, of which the following is a specification, reference being had to the accompanying drawing, forming part thereof.

In the drawing:

Fig. 1 is a perspective view of a fixture showing my new design, and

Fig. 2 is an enlarged sectional view taken on the line 2—2 of Fig. 1.

The dominant feature of the design is the three-step drop of the rim.

I claim:

The original design for a lavatory as shown and described.

CHARLES R. CRANE, II.
